DESIGN FOR A POCKETED BELT

Joseph Buegeleisen, Detroit, Mich.

Application March 25, 1940, Serial No. 91,228

Term of patent 14 years

To all whom it may concern:

Be it known that I, Joseph Buegeleisen, a citizen of the United States of America, residing at Detroit, county of Wayne, and State of Michigan, have invented a new, original, and ornamental Design for a Pocketed Belt, of which the following is a specification, reference being had therein to the accompanying drawing, forming a part thereof, wherein:

The opposite side of the belt is the same as the side shown.

The characteristic feature of my design resides in the combination on the belt disclosed of the rosette and streamer trimmed pocket members on each side thereof, as shown.

I claim:

The ornamental design for a pocketed belt, substantially as shown and described.

JOSEPH BUEGELEISEN.
